UNITED STATES PATENT OFFICE

NORTON A. MEARS, OF CHICAGO, ILLINOIS, ASSIGNOR TO CHICAGO FORGING & MANUFACTURING CO., OF CHICAGO, ILLINOIS, A CORPORATION OF ILLINOIS

HOOD LATCH

Application filed November 7, 1930. Serial No. 493,946.

My invention relates to a latch or closing means. One application thereof is as a hood latch for an automobile hood closure. One object is the provision of such a latch or closure which shall be efficient and positive in its action and which shall be easily actuated. Another object is the provision of a latch or locking device which shall yieldingly draw a lower edge of a hood closure 10 downwardly and inwardly toward a limiting abutment. Another object is the provision of a closure which includes an interior locking device and an exterior control member adapted also to lift the closure to which 15 the locking device is applied. Other objects will appear from time to time in the course of the specification and claims.

I illustrate my invention more or less diagrammatically in the accompanying drawings, wherein

Figure 1 is an inside view illustrating the device in locking position;

Figure 2 is a section on the line 2—2 of Figure 1;

Figure 3 is a similar section showing the parts in unlocked position; and

Figure 4 is a section on the line 4—4 of Figure 3.

Like parts are indicated by like symbols throughout the specification and drawings.

Referring to the drawings, A generally indicates a frame of an automobile which is provided with an upwardly extending abutment A¹. B indicates a side of an automobile hood closure, the lower edge B¹ of which is adapted to be opposed exteriorly to the abutment A¹. Mounted on the inner face of the hood closure B is the lock assembly plate or support generally indicated as C.

It includes the bottom plate or horizontal portion C¹ cut away as at C² and upwardly extending side portions C³ terminating in ears C⁴ which may receive the bolts or rivets C⁵, whereby the assembly is secured in place.

C⁶ is a similar securing ear at the bottom of the assembly. Each of the side portions C³ have an ear C⁷, the two ears being approached and receiving the pivot member C⁸ passing therethrough. C¹⁰ indicates a 50 curved portion of the member C¹ which

serves as an abutment lip for the below described latch.

Mounted on this pivot member C⁸ is the handle and lever element generally indicated as D. It includes the outwardly extending handle lever portion D¹ which may terminate in the finger engaging ring D². D³ indicates an inner enlargement slotted as at D⁴. It will be understood that the hood B is cut away as at B² in order to permit 60 the passage of the handle member or lever D¹.

E generally indicates a latch member proper, herein shown as of heavy wire or bar stock. It includes a lower hook member E¹, an intermediate shoulder portion E² which is connected by the angular portion E³ with an upper shank E⁴. The top of the shank is laterally recurved as at E⁵, the end E⁶ of this laterally recurved portion 70 passing through the slot D⁴. It is normally held against the inner end of said slot as by the spring generally indicated as E⁷ which includes a bend E⁸ abutting against one end of the aperture D⁴, the coil spring portions 75 E⁹ and the recurved ends E¹⁰ which are formed to engage the end E⁶ of the latch and hold said end at the inner end of the slot D⁴.

G indicates any suitable keeper, herein 80 shown as including a stem G¹ outwardly extending from a base or plate G², which may be secured in any suitable fashion to the automobile, at a position properly spaced inwardly from the hood B.

It will be realized that whereas I have described and shown a practical and operative device, nevertheless many changes might be made in the size, shape, number and disposition of parts without departing from the 90 spirit of my invention. I therefore wish my description and drawings to be taken as in a broad sense illustrative and diagrammatic rather than as limiting me to my specific showing.

The use and operation of my invention are as follows:

In locking automobile hoods, I find it desirable to provide a hood latch which is positive in its action and which tends to 100

draw a lower edge of the hood closure downwardly and inwardly. I find it also desirable to associate with a concealed or inside hood latch an exterior handle or control member which serves to lift the hood after the latch has been released.

It will be seen from a consideration of Figures 2 and 3 that when the hook E^1 is in locking position, as in Figure 2, the handle D^2 is at the lower extremity of its rotation. The spring E^7 draws the hook E^1 upwardly against the bar or pin G^1 , urging its upper portion E^6 upwardly in the slot D^4 . The inclination of the axis or line along which this thrust is directed, as defined by the position in which the slot is shown in Figure 2, tends to draw the lower edge B^1 of the hood B inwardly as well as downwardly toward the abutment A^1 . The parts are so proportioned also that when the handle is lowered to full locking position, the member E^6 will be to the right of a line passing through the junction between the opposed hook and pin, and the pivot C^8 , referring to the parts in the position in which they are shown in Figure 2.

When the operator wishes to release the latch and lift the hood, he merely rotates the lever D^2 into the position in which it is shown in Figure 3. He thereby moves the upper end or shank E^4 of the hook inwardly away from the hood, and withdraws the hook E^1 outwardly toward the hood. The effect of the initial upward movement of the handle C^2 is to cause an almost directly downward movement of the hook C^1 until it is freed from contact with the pin G^1 . An additional effect of the spring E^9 is to tend to hold the hook against rotation in relation to the member D^3 . The aperture C^2 is of sufficient length to permit a lateral movement of the shank of the hook and as the handle C^2 is rotated the hook is thrown laterally in said slot.

When the handle D^2 is in the position shown in Figure 3 the hook is out of vertical alignment with the member G^1 , and the shank E^2 is at the outer end of the aperture C^2 . When the operator lowers the handle D^2 the frictional engagement of the portion E^6 with the member D^3 causes a lateral movement of the hook E^1 which positions it beneath the pin G^1 . Further rotation of the handle D^2 then draws the hook E^1 upwardly into locking contact and the end E^6 is carried past a line drawn through the pin G^1 and pivot C^8 , thereby holding the parts in locked position.

Note that downward movement of the hook, and therefore upward movement of the handle D^2 , is limited by the engagement of the portion E^3 of the hook member with the top of the member C^1 . This is shown for example in Figure 3. On the other hand the pad portion D^{10} by engaging the shank

E^4 , limits the downward movement of the handle D^2 . This prevents battering of the handle against the top or bottom of the aperture B^2 and thus prevents marring of the finish on the handle or of the finish on the hood.

I claim:

1. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion, a latch pivoted to said lever within the hood, said latch including a hook, said lever being slotted to receive an end of said latch, and yielding means for holding said latch end at a predetermined position in said slot.

2. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion, a latch pivoted to said lever within the hood, said latch including a hook, said lever being slotted to receive an end of said latch, and yielding means for holding said latch end at a predetermined position in said slot, including a spring having a portion engaging one end of the slot, and a portion engaging the slot penetrating portion of the latch.

3. In a hood closure securing means, the combination, with a hinged door member to be latched, of a keeper within the hood, a latch actuating lever pivoted to said hood, for rotation about a horizontal axis generally parallel with the inner face of the hood, including an outwardly extending handle portion, a latch pivoted to said lever within the hood, and including a hook and a shank therefor, a guide inwardly projecting from the hood, apertured to permit the passage therethrough of said shank, said shank including an offset portion engaging the top of said guide, and limiting the downward movement of the latch, and opposed portions of latch and lever adapted to limit the rotation of the lever in the closing direction.

4. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion and an inwardly extending slotted portion, and a latch within the hood, including a hook and a shank portion penetrating said slot.

5. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion and an inwardly extending slotted portion, and a latch within the hood, including a hook and a shank portion penetrating said slot, and yielding means for normally urging said penetrating shank portion upwardly or inwardly along said slot. 70
6. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion and an inwardly extending slotted portion, a base member within the hood, to which said lever is pivoted, said base member including an apertured guide portion below said pivot point, a latch including a hook positioned below said guide portion, a shank passing through the aperture in said guide portion and pivoted within the slot. 80
7. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion and an inwardly extending slotted portion, a base member within the hood, to which said lever is pivoted, said base member including an apertured guide portion below said pivot point, a latch including a hook positioned below said guide portion, a shank passing through the aperture in said guide portion and pivoted within the slot, said shank including an offset portion adapted to engage said guide portion and to limit the downward movement of the hook. 85
8. In a hood closure securing means, the combination, with a hinged door member to be latched, of a keeper within the hood, an actuating lever pivoted to the hood, for rotation about a horizontal axis generally parallel with the inner face of the hood, including an outwardly extending handle portion and an inwardly extending portion, a base member within the hood, to which said lever is pivoted, said base member including an apertured guide portion below said pivot point, a latch including a hook positioned below said guide portion, a shank passing through the aperture in said guide portion and pivoted to said inwardly extending portion, said shank including an offset portion adapted to engage said guide portion and to limit the 90
